UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN ARM FOR CHANDELIERS OR LIGHT-REFLECTING BOWLS.

46,476.

Specification for Design.

Patented Sept. 29, 1914.

Application filed July 18, 1914. Serial No. 851,829. Term of patent 3½ years.

To all whom it may concern:

Be it known that I, CHARLES E. JONES, a citizen of the United States, residing at Chicago, in the county of Cook and State of Illinois, have invented a certain new, original, and ornamental Design for an Arm for Chandeliers or Light-Reflecting Bowls, of which the following is a specification, reference being had to the accompanying drawing, forming a part thereof.

The figure is a perspective view of an arm

for chandeliers or light reflecting bowls, showing my new design.

I claim:

The ornamental design for an arm for chandeliers or light reflecting bowls as shown.

CHARLES E. JONES.
